[57] CLAIM

The ornamental design for a combined line cutter and retractable needle, as shown and described.

DESCRIPTION

FIG. 1 is a top plan view of a combined line cutter and retractable needle, showing my new design;

FIG. 2 is a top plan view with the needle in the extended position;

FIG. 3 is a bottom plan view of FIG. 1;

FIG. 4 is a left side elevational view, the right side being a mirror image thereof;

FIG. 5 is a left side elevational view with the needle in the extended position;

FIG. 6 is a rear elevational view of FIG. 1; and,

FIG. 7 is a front elevational view thereof.

FIG. 1

FIG. 2

FIG. 3
